UNITED STATES PATENT OFFICE.

ALBERT H. EMERY, OF STAMFORD, CONNECTICUT.

PROCESS OF CONSTRUCTING AND ASSEMBLING GUNS.

SPECIFICATION forming part of Letters Patent No. 727,766, dated May 12, 1903.

Application filed November 2, 1897. Serial No. 657,263. (No model.)

To all whom it may concern:

Be it known that I, ALBERT H. EMERY, a citizen of the United States, and a resident of Stamford, in the county of Fairfield and State of Connecticut, have invented a new and Improved Process of Constructing and Assembling Guns, of which the following is a specification.

My invention consists in a mode whereby 10 linings and other parts of guns are assembled and condensed, either or both, by means of pressure of liquid either alone or in conjunction with moving rollers or mandrels, or both, for the purpose of increasing the strength and 15 elastic limit and producing permanent initial strains of compression on the interior and tension on the exterior, first of the separate parts and finally of the combined body.

It has been a common practice to set and 20 expand linings or shells of ductile sheet metal, such as copper or brass, within a hollow body or within a mold employed to give form to such shell. It has also been common to employ hydraulic pressure for testing boilers 25 and other hollow bodies. My invention is distinguished from these practices in the particulars hereinafter explained.

The bores of bronze guns have heretofore 30 been condensed by myself and others by forcing a mandrel through them. This process has not so far enabled the constructor to condense the metal to any considerable depth from the bore, but often injures the surface from the great vibrations and distortion of 35 the metal produced as the dies or mandrels are forced backward and forward over the surface, the action being so great as to partially break up and disintegrate the metal at and near the surface, while not extending the 40 condensation to any considerable depth. To avoid these evils, I have devised the process hereinafter described, and illustrated in the accompanying drawings, by which I not only condense the interior surfaces of bores and 45 linings of guns without injury, but I condense these parts clear through and greatly increase the limit of elasticity and ultimate strength of the whole piece, whether such piece constitutes the lining or other part of the gun or 50 is in itself a complete gun. At the same time the piece being treated by this process will, if taken from the gun, be found to have

strains of compression on the interior and tension on the exterior, which is often directly the reverse of the strains in a piece before 55 treatment by my process. Moreover, this process enables me to leave the whole gun under strains of compression on the interior and tension on the exterior, which is so greatly to be desired. 60

In the accompanying drawings, Figure I is a longitudinal sectional elevation, and Fig. II a transverse section on the line II II, Fig. I, of such portion of the apparatus as is necessary to illustrate my invention. Figs. III and 65 IV are detail longitudinal sections, on a larger scale, illustrating different forms of packing used in carrying out my invention. Fig. V is a longitudinal section of a gun with apparatus for applying and locating liquid-pressure 70 therein. Fig. VI is a longitudinal section of a gun with apparatus for applying pressure by rollers and liquid combined.

46 shows a large cylinder, of gun iron or steel, bored out and fitted to receive the 75 strengthening-rings 47, of tempered steel, which are made of any number of series required for the necessary strength. As here shown there are four.

48 and 49 show tubes, of tempered steel, 80 suitably prepared and inserted in the apparatus used in the construction of the gun.

28 shows a bore-lining undergoing condensation. This may be of soft steel or chilled bronze or other suitable material. It is first 85 dressed to the size of the interior tube 49 and then carefully bored and inserted ready for condensation. Before being inserted it may be provided with a packing-groove and packing, (shown at 60,) as is also the lining-tube 49, so that these parts may be inserted and taken out by the aid of liquid-pressure, as I have described in applications, designated Serial No. 505,155, filed March 26, 1894, and Serial No. 11,904, filed April 6, 1900. In 95 condensing the tubes 28 the heavy pressure required to sufficiently condense them causes the metal to flow longitudinally, for which reason the piece must be firmly secured against this flowing by collars or other suitable means applied at its ends. 46^a shows a collar which secures this piece at one end. A similar one may be used at the other end. When the piece 28 has been inserted and

these collars secured against the ends thereof, the condensing-bar 50 is inserted. This bar has around it an annular space or spaces 53 53^a, into which liquid is forced by the pump-
5 plunger 51 through the passage 52 into the annular space 53 or through the pipe 56^a and passage 56 into the annular space 53^a. One of these spaces may, if required, extend the whole length of the lining 28 and the required
10 pressure to fully condense the same be applied at once. If the bore is condensed in the gun in this way instead of in the condensing apparatus, the pressure to condense the piece thoroughly is too great to be applied
15 to the whole length at once with safety to the gun. The apparatus for condensing, however, may be made so strong as to resist the pressure, when condensing is best performed by allowing the pressure to act on the whole
20 interior surface at once. It will often be desirable to use a greater pressure on these linings in condensing than could be properly applied to the apparatus on the whole length of the bore-lining at once. To avoid applying
25 this pressure to the whole length of the bore-lining at once and yet make use of the heavy pressure desired, the annular spaces 53 or 53^a may be short, as here shown, or very much shorter. Condensation then takes place
30 by condensing with small pressure the piece 28 throughout its whole length by apparatus which will do so at once, as described, or by condensing a short length at a time by the apparatus as shown and moving this along from time
35 to time as the part around it becomes condensed until the whole has been condensed. After the condensation has been performed with moderate pressure greater pressure may be used in one of these annular spaces than
40 could at first be applied without causing the metal to flow away, and when the piece is condensed in the gun I prefer usually to go over it several times, condensing it in sections with one pressure and afterward repeating
45 with larger pressure, increasing the pressure each time the surface is gone over and allowing the surface operated on at any time to overlap that already condensed. When the condensing is done in the gun, this plan may
50 be used successfully, especially if the final condensing be done with apparatus which acts on a short space only at any one time, so as to load only a small portion of the gun's walls at once, when the adjoining parts of the
55 gun will aid those parts in resisting the heavy pressure put upon the lining opposite them. It will sometimes happen that the part being pressed will flow away under these pressures. To prevent this flowing, three annular spaces may be used in conjunction, the middle one having a very heavy pressure, and the two outer spaces, which are close adjoining the other, having lighter pressures upon them and no more than the metal will
60 hold without flowing sensibly. This will prevent the heavy pressure on the interior space from causing the metal to flow away, and will

thus permit the heavy condensation. When more than one annular space is used around the bar 50, the walls between these spaces should be as narrow as they can be made and have them stand the severe strains imposed. Packings are shown at 54 in Fig. I. Fig. III shows an enlarged view of one of these packings. It may be made of three or more pieces, as here shown, the parts 57 57 being of soft steel or copper, 58 a thin sheet of brass or copper, and 59 leather. A packing of this nature may be used in the grooves at 60 around the bore-lining 28 and the lining of the tube 49 for the purpose of inserting or removing them, as desired, and when thus used it may take the form shown in Fig. IV, the parts of steel or copper 57 being retained and the leather 59 introduced with or without the intermediate sheet of metal 58. The leather may be replaced by any other suitable elastic material. The liquid to be used had generally best not be very fluid, in consequence of the difficulties in retaining it. The packing 54 may be of such kind as to require the enlargement 55, forming the end of a chamber, to be removable, for which purpose it may be in the form of a collar and threaded, as shown at 62, whereby it may be taken off to apply the packing 54 and then replaced. After the lining 28 has been suitably condensed it is removed from the condensing apparatus by forcing liquid between it and the tube 49 with the necessary pressure to release it sufficiently so that it may be slipped out by hydraulic pressure or by other means. The process of doing this and inserting it in the gun has been fully described by me in my applications above mentioned.

The plunger 51 may be forced down the bar 50 to force the liquid or paste into the annular space 53 by a screw or any other suitable means. Hydraulic pressure operating a piston in the bar 50 may accomplish this very well and is perhaps the most desirable way, the bar itself forming a cylinder in that part which is not here shown, with a piston placed on the rod 51 of sufficient area to force it down. This same apparatus may be made for condensing larger linings by taking out the tube 49, which itself may be a gun-lining. As many of these removable lining-tubes may be used as the nature and variety of the guns being constructed shall render desirable. After the lining has been inserted in the gun and before final boring and rifling the gun should be thoroughly tested and strained by hydraulic pressure suitably applied, as I will now describe. The bar 50 for this purpose may have an enlarged surrounding sleeve 35^b, which is screwed into the gun in place of the breech-block or into a collar screwed therein, the bar itself extending nearly or quite to the muzzle of the gun; but I prefer the construction shown in Fig. V, which admits of longitudinal motion of the bar. Around it are provided several annular spaces in that part which nearly fits the bore. Four or five of

these spaces may advantageously be used. The packings 54, &c., will prevent the liquid from running from one space into another when pressure is applied. For the initial 5 pressure the liquid may be allowed to act on the whole bore from the packing at the rear of the chamber around the bar 50 clear to the packing at the muzzle of the gun around the same bar, and thus the whole interior of the 10 gun be loaded by such pressure as the bore of the chase should endure. This pressure should be sufficient to cause a permanent set throughout the whole length of the chase or muzzled part of the gun to the extent desired, 15 which will increase the limit of elasticity and ultimate strength and put the proper strains of compression on the interior and tension on its exterior. After this pressure has been put on the interior of the gun a higher pressure 20 is used on the part of the bore toward the chamber and still higher pressures on the chamber itself and the portion of the bore immediately adjoining, constituting that part of the bore and chamber which are loaded 25 with heavy powder-pressure at the time of firing. It will generally be found sufficient to insert at once the single bar 50 with five or six annular spaces, one of which covers the whole of the chamber, the rest covering 30 all of the bore except so much as will be required for the small rings which separate the different annular spaces around the bar 50. The pressure from the liquid may then be applied in all these spaces at once, increasing 35 in each from the muzzle to the chamber, having such pressure in each as that part of the gun should be tested with. These pressures may all be put on at once, if desired, each part being fully strained with the maximum 40 pressure it is to be strained with, and when thus strained with this pressure allowed to remain so for a suitable time. Similar powder-pressures, acting, as they do, only for a small portion of a second, are not likely to 45 again disturb the form of the gun. The gun having been thus fully strained, the bar 50 should be removed, the chamber and bore carefully reamed to the exact size required, and the rifling performed, when the breech 50 apparatus is assembled therewith and the gun is ready for use.

It will be seen that the process described for condensing the bore-lining is directly applicable to condensing the interior of the gun-barrel 23 or other part of the gun throughout its whole or any part of its length and straining it to position as desired. This may often be advantageously done even when the piece is made of soft tempered steel, as the parts 55 when so strained resist further expansion with very great force, more force being required even to again move them permanently than the original force used in condensing and expanding, the limit of elasticity and ultimate strength having both been greatly increased by this process of condensing and outward expansion.

The chamber-lining 27 and bore-lining 28 may either or both be condensed by being inserted into a suitable receptacle and there 70 subjected to a very heavy liquid-pressure acting upon the whole of the interior surface and from the interior outward, when the exterior would be firmly pressed against suitable retaining-walls to endure this pressure. 75 This pressure should be so great as to make the metal sensibly dense, and acting from the interior outward will cause strains of tension on the exterior and compression on the interior when the piece is removed from the 80 receptacle in which it is condensed. These walls will require to be of very great strength, as the pressure necessary to properly condense these linings should be from sixty thousand to one hundred and twenty thousand 85 pounds to the square inch. By expanding these linings thus against the walls of the retaining apparatus and with these great pressures the lining is made true and smooth with the retaining-walls and is free from all 90 unsymmetrical strains and when removed will have tension on its exterior both longitudinal and tangential and compression on its interior both longitudinal and tangential.

Should the chamber-lining 27 or bore-lining, 95 or both, be made of metal which would be improved by cold condensing, they may be condensed before insertion or after, as desired, and in cases where they are very thin and the chamber and bore are of large diameters 100 they may be condensed by the process of rolling, either in the supplementary apparatus or after they are placed in the gun. The rollers in such case had best be in pairs, with an adjustment for throwing their centers 105 apart during the process of rolling, so that as the arbor rotates which carries them around over the surfaces of the bore or chamber lining and the material becomes condensed the distance between the rollers may be gradually 110 increased to increase the pressure of the surface being condensed. When this process of condensing by the use of the rollers is used as thus described, the condensing of the metal may be aided by applying liquid-pressure on 115 the interior of the gun bore or chamber lining at the same time that the rollers are acting, the combined pressure of the liquid acting on the surface around the roller with the pressure of the roller, giving much more 120 effective condensation than will the liquid-pressure or roller-pressure when applied alone. When this process is adopted, the arbor which carries the roll or rollers should have packings made to stand heavy pressures 125 through which it slides backward and forward as it rotates and moves longitudinally to bring the roll or rollers over all parts of the bore or chamber lining, the liquid-pressure acting on the whole interior surface of the 130 parts while the rolling proceeds. Fig. VI shows a longitudinal section of the gun with an apparatus of this kind in operation.

Apparatus can be provided to put liquid-

pressure on a portion only of the bore or chamber lining at a time and rolling at this part be proceeded with and afterward the apparatus so moved along to condense the other portions of the bore or chamber lining; but I think it will in general be found better to put the liquid-pressure on the whole interior of the piece being condensed at the same time and then allow the roll 50^b or rollers 10 while this pressure is continued to pass over the whole interior surface of the piece being condensed.

When used without radial adjustment of the rollers, the lining 27 is bored slightly 15 larger at the rear end, where the rollers are introduced. The chamber is then tightly closed by means of the packing described, the fluid-pressure applied, and the arbor simultaneously rotated and advanced by suitable mechanism, the lining (or other part of 20 the gun, as the case may be) being thus expanded to position and condensed sufficiently by advancing the rollers from one end to the other and back again, or a second arbor with 25 rollers having slightly more projection may be applied and the operation repeated as often as necessary.

While referring in this specification to liquid as the medium of applying the required 30 heavy pressure, I desire to be understood as including any suitable liquid or gas or other material having sufficient fluidity for the purpose. Under the very heavy pressure employed this condition will include some materials usually termed "solids." If a gas be used, the pressure may be produced either by mechanical means or wholly or in part by the generation of the gas in a reservoir of sufficient strength.

40 I am aware that liquid-pressure has been used for shaping thin metal shells and for fitting thin sheet-metal linings of lead, copper, or brass to press cylinders to prevent their leaking; but the pressures required for 45 this do not condense the metal, being very small compared with the pressure previously used to draw the shells or to roll the plates of which such linings are made.

Having thus described my invention, the 50 following is what I claim as new therein and desire to secure by Letters Patent:

1. In the manufacture of guns, the process of treating the walls of the bore or chamber of the gun or the bore-linings or chamber-linings of the gun, which consists in applying heavy liquid-pressure thereto, sufficient 55

to condense such part, and greatly increase its limit of elasticity and ultimate strength.

2. In the manufacture of guns, the process of treating a chamber or bore lining, which 6 consists in introducing the part to be treated into a suitable condensing apparatus, introducing into the interior of the part to be treated, heavy liquid-pressure sufficient to force the walls of the part firmly against the 6 surrounding apparatus, to condense the metal of said part being treated, and greatly increase its limit of elasticity and ultimate strength.

3. The process of expanding the inner parts 7 of a gun against the outer parts thereof, which consists in introducing into the inner parts liquid under different pressures, in different portions of the inner parts, sufficient to force the inner parts out against the outer 7 parts and give permanent extension to the inner parts, and strain them to their proper position, increasing their limit of elasticity and ultimate strength and firmly securing the parts together.

4. The process of expanding the interior parts of a gun, which consists in introducing into the interior thereof heavy hydraulic pressure sufficient to force the interior parts outward, the pressure used in the rear portion being greater than that used in the front portion, the pressures being sufficient to permanently enlarge the parts into which they are introduced.

5. The process of expanding the bore or 9 chamber lining or other part of a gun outwardly by means of heavy hydraulic pressure acting on the interior thereof, which consists in introducing into the interior thereof of a straining - bar, introducing around the 9 bar three or more packings forming two or more chambers between said packings, introducing different degrees of heavy hydraulic pressure into the respective chambers so formed and expanding the metal around said chambers to the extent desired.

6. The process of condensing the bore or chamber lining or other part of the gun, which consists in introducing into the interior thereof heavy liquid-pressure and at the same time rolling it on the interior with a roller or rollers to condense it.
